UNITED STATES PATENT OFFICE.

JACOB N. ISENBERGER, OF LANCASTER, PENNSYLVANIA.

DESIGN FOR AN ANTI-SASH-RATTLER.

45,383.

Specification for Design.

Patented Mar. 10, 1914.

Application filed December 12, 1913. Serial No. 806,334. Term of patent 3½ years.

To all whom it may concern:

Be it known that I, JACOB N. ISENBERGER, a citizen of the United States, residing at Lancaster, in the county of Lancaster and State of Pennsylvania, have invented a new, original, and ornamental Design for an Anti-Sash-Rattler, of which the following is a specification, reference being had to the accompanying drawing, forming part thereof.

The figure is a perspective view, showing my new design.

I claim:

The ornamental design for an anti-sash rattler, as shown.

JACOB N. ISENBERGER.
